IRA E. McCABE, OF CHICAGO, ILLINOIS

SAFETY PRESSURE-ACTUATED SWITCH

Application filed July 9, 1925. Serial No. 42,405.

This invention relates to improvements in safety appliances and more particularly to a safety pressure actuated switch such as described in my prior pending application Serial No. 19,310, filed March 30, 1925.

In the said prior application a two element electric control is described in the main circuit for controlling an electrically operated domestic oil burner heater, and this invention is shown and described herein as employed in one element of such a control. In fuel burning systems of this general character a tilting mercury tube switch is employed to close the operating circuit when the burner flame is ignited and break the said circuit when the flame becomes extinguished, preferably actuated by a pressure or Bourdon tube connected to a thermal coil arranged in proximity to the burner flame whereby the heat of the flame causes the Bourdon tube to expand and rock the switch with a snap movement into closed position and upon failure of the flame the coil cools causing the tube to contract and snap the switch into open position. The improvement made the subject of this application is providing means between the pivoted rocking member carrying the mercury switch tube and the free end of the Bourdon tube whereby the first expanding movement of the Bourdon tube, when the pressure therein reaches a certain degree, will actuate the switch mechanism to rock the switch tube into closed position and allow further expanding movement of the Bourdon tube therebeyond. If the pressure within the Bourdon tube becomes too great there is danger of injuring or destroying it and this invention contemplates mechanism whereby the expansion of the Bourdon tube as it approaches the danger limit will actuate the switch mechanism to rock the tube switch to open position so that the flame is extinguished when its heat becomes too great for the safety of its control and as thermal coil cools and the Bourdon tube contracts it returns the actuating mechanism of the switch to the first relation to the tube in the open position.

With these and other objects in view, reference is made to the accompanying drawing

which illustrates a form of this invention as embodied in an electrically operated fuel burning system of the character described. However this invention is not limited to this particular embodiment as it can be applied to any other use of tilting mercury tube switches actuated by any form of prime mover instrumentality.

In the drawings:

Figure 1 is a view in front elevation of one form of a pressure actuated snap movement mercury tube switch, with cover removed and the mercury switch tube shown in dot and dash lines in open position as constructed in accordance with this invention.

Figure 2 is a detail view of the parts as shown in Figure 1 with the front plate and mercury switch tube removed.

Figure 3 is a similar view showing the position assumed by the moving parts upon normal expansion of the Bourdon tube in which the switch tube is in closed position.

Figure 4 is a similar view showing the position assumed by the moving parts upon further expansion beyond the normal and approaching the danger limit of the Bourdon tube in which the switch tube has been thrown to open position.

Figure 5 is a view similar to Figure 1 of another form illustrating a modification in the actuating mechanism.

Figures 6, 7 and 8 are views illustrating this form of actuating mechanism in positions corresponding to Figures 2, 3 and 4.

Figure 9 is a view in vertical section illustrating the application of this invention to a stack control.

Figure 10 is a view in end elevation of the thermal coil shown in Figure 9.

Figure 11 is a view in front elevation of Figure 9, with the casing cover removed.

Figure 12 is similar view of a modification of Figure 11.

The embodiment of this invention, as illustrated, shows in Figure 1 a casing 1 in which is mounted a pressure or Bourdon tube 2 having a connection 3 to the source of pressure and leading in wires 4 and 5 from a commercial or other electric circuit connected to binding posts 6 and 7 which in turn

are connected by flexible leads 8 to the terminals 9 entering one end of a mercury switch tube 10, shown in dot and dash lines, which switch tube is mounted on a snap movement mechanism generally similar to that shown and described in my prior pending application Serial No. 585,698, filed September 1, 1922, which is actuated by the expansion and contraction of the Bourdon tube in response to the variations of pressure. Improvements have been made in the snap movement actuating mechanism whereby in the normally contracted position of the Bourdon tube the mercury switch tube is positively held in tilted position with the mercury accumulated in the end opposite the terminals so that the switch is open and upon the expanding of the Bourdon tube the mercury tube is rocked to a degree sufficient to cause the mercury to flow into the end containing the terminals and close the circuit therethrough in which position it is positively held until the Bourdon tube either contracts to the first position, rocking the switch tube to open position, or expands beyond the safety limit whereupon such further movement the mercury switch tube is snapped back into open position and positively held there while the moving parts, as the Bourdon tube contracts, assume their first relation to the mercury tube. As aforesaid this mechanism is particularly adapted to devices in which the closing of the electric circuit is directly responsive to the pressure, or temperature causing the pressure, and in which the pressure reduces to normal upon the breaking of the circuit. The switch snap mechanism may be said to perform three functions; namely, normally holding the switch in open position, upon pressure increasing closing the circuit and holding the switch in closed position; upon pressure becoming too great throwing the switch to open position and holding it in open position and as pressure decreases allowing the moving parts of the mechanism to assume the first or normal position without affecting the switch. The relation between the switch mechanism and Bourdon tube is adjustable in the same manner as previously described in my prior application Serial No. 538,916, filed February 24, 1922, so it need not be described here and therefore the adjustment is not particularly illustrated.

The switch operating mechanism is mounted on a base plate 11 mounted on the rear wall of the casing and includes a rocking member 12 in the form of a bracket plate mounted to rock on a central pivot extending outward from the base plate, having a right angular extension 13 from the upper side upon which the mercury switch tube is carried. An operating member 14 is mounted on a pivot therebelow extending from the base plate and having a link 15 pivotally mounted near one end having a roller connection 16

at its free end with the rocking member 12 with which contact is maintained by a coil spring 17 one end of which is secured to the base plate and the other attached to a rotatable anchor 18 carried centrally upon said link, the portion of the operating member extending on the opposite side of its pivot from the link depends therebelow and is provided with a slot in which is adjustably and pivotally mounted a safety arm block 19. 75 An operating lever 20 is pivoted to the base plate at one end approximately in line with the rocking member with a post 21 extending outward from the base plate between the rocking member and operating lever pivot 80 and another post 22 of similar height extends outward from the base plate on the outer side of the roller carrying link to which posts a front plate 23 is secured by screws entering the posts 21 and 22 which plate also 85 engages and rigidly maintains the outer ends of the respective pivots extending from the base plate.

A mercury switch tube 10 having terminals 9 entering one end is carried between clamps 90 preferably extending downward from a plate 24 adjustably secured upon the right angular extension 13 of the rocking member, which switch tube and carrying plate is shown in dot and dash lines in Figure 1. The rocking 95 member 12 on the side adjacent the operating lever is provided with two spaced apart projecting arms 25 extending on either side of the post 21 carried on the base plate between said member and operating lever pivot 100 adapted to engage said post to limit the rocking movement of said member, the opposite side being provided with angular converging edges 26 which would normally meet in a plane through the rocking member pivot 105 parallel to the switch tube carrying extension 13 but before the edges meet they are cut out as shown at 27 to receive roller 16 mounted between the free ends of the side plates forming the pivoted link 15 which side 110 plates at the other end engage on opposite sides of the operating member 14 and rotate on the link pivot carried thereby. The spring 17 maintains the roller 16 in engagement with the inclined or curved edges of the rock- 115 ing plate 12.

An operating link 28 is pivotally connected at one end to the movable extremity of the Bourdon tube and at the other intermediate the extremities of the operating lever 120 20, preferably adjacent the pivoted end thereof. The free end of the operating lever 20 is provided with a bent back projection 29 adapted to travel over an arcuate plate 30 secured upon the front plate 23, as shown in dot and dash lines. The projection forms an indicator pointer and the portion of the plate 30 over which it travels is provided with a scale to indicate the pressure, or temperature generating the pressure, within the 130

Bourdon tube causing the movement of the free end of the operating lever through the operating link as the Bourdon tube expands and contracts. A safety arm block 31 is pivotally mounted on the free end of the operating lever adapted to travel under the indicator index plate 30. A safety arm, 32 preferably in the form of a rod, as shown in Figures 1, 2, 3 and 4, is mounted to travel through the safety arm blocks 19 and 31 pivotally carried on the operating member and operating lever, respectively. The rod is adjustably secured in block 19 by a set screw 33 and is mounted to slide through block 31 with its end enlarged to engage the block and limit the movement of the operating member away therefrom. A friction contact is provided between block 31 on the lever and the rod 32 preferably in the form 20 of a spring arm 34 secured to the block with its free end pressing upon the arm, which spring is of sufficient length as the Bourdon tube contracts to normal to first engage the safety arm block 19 on the operating member 14 and then rotate that member about its pivot until the moving parts are in the position shown in Figures 1 and 2.

The operation of the device is as follows: There being no pressure in the Bourdon tube, the tube is contracted which through link 28 has moved the free end of the operating lever to cause the operating member to be rocked on its pivot through contact of the spring arm 34 with the safety block 19 thereby elevating the free end of link 15 causing the roller carried thereby to engage in the cut out portion of the rocking member and rotate it about its pivot until the upper arm 25 engages the post 21, thereby rocking the mercury switch tube to open position. As pressure accumulates in the Bourdon tube it expands causing its free end to move toward the side wall of the casing and as it increases this movement transmits a similar movement to the free end of the operating lever 20. As the operating lever moves outward the indicator pointer travels over the scale on the arcuate plate and at the same time exerts a pull on the safety block 19 on the operating member 14 through the frictional engagement of the spring arm 34 of the block 31 upon the rod 32 thereby rocking the operating member upon its pivot causing the pivoted end of the link 15 to descend which through its roller 16 engaging in the cut out portion 27 of the rocking member 12 causes this member to rotate upon its pivot rocking the mercury switch tube until the end containing the terminals is lower than the other end and the mercury flows about the terminals and closes the circuit.

The rotation of the rocking member 12 is limited by contact of the lower arm 25 with the post 21 which holds the switch in closed position as long as there is sufficient pressure in the Bourdon tube. This closed

position is shown in Figure 3 of the drawing. If the pressure in the Bourdon tube decreases then the parts return to the position illustrated in Figure 2, upon contraction of the tube. On the other hand, should the pressure increase beyond that necessary to rock the switch tube to closed position the further outward movement of the free end of the Bourdon tube causes the safety block 31 on the operating lever 20 to ride over the safety arm rod 32 and this pull of the Bourdon tube overcomes the friction between the spring arm 34 carried by safety block 31 and the rod 32 fixed to the safety block 19 on the operating member. It is necessary to provide the spring 17 for the roller carrying link 15 of greater tension than the friction between the arm 32 and spring arm 34 to allow independent movement of the block 31. As the pressure decreases the safety block 31 through the friction of the spring arm 34 upon the safety arm rod 32 causes the operating member to rock and thereby return the rocking member to the position shown in Figure 2.

Should the pressure in the Bourdon tube continue to increase beyond the safety limit the tube will be injured or destroyed. To prevent such an occurrence, the safety arm rod is so adjusted in safety block 19 of the operating member that before the pressure reaches the critical danger limit of the tube, the enlarged end of the safety arm rod 32 is engaged by the safety block 31 on the operating lever and further outward movement is then imparted to the operating member 14 which causes a downward pull on the link 15 overcoming the tension of the spring 17 causing the roller 16 to ride over the lower edge of the cut out portion and engage the angular lower edge 26 of the rocking member 12. The pressure of the roller against the angular edge causes the rocking member to snap into the position shown in Figure 4 with the upper arm 25 in engagement with the post 21, which position of member 12 is the same as shown in Figure 2, and the circuit is broken.

As the Bourdon tube contracts from this extreme position the safety block 31 of the operating rod rides back over the safety arm rod 32 overcoming the friction between the spring arm 34 and safety arm rod 32 until the free end of the spring arm 34 of the block 31 engages the safety block 19 of the operating member 14 which then imparts an upward movement to the roller carrying link 15 causing the roller 16 to ride up over the inclined edge and into the cut out position 27 of the rocking member 12, bringing the moving parts of the mechanism into the original position, illustrated in Figures 1 and 2, without moving the mercury switch tube from its open position.

The form illustrated in Figures 5 to 8 in-

clusive operates in the same general manner as that shown in the first four figures, the only difference being in the sliding connection between the operating lever 20 and the operating member 14. As shown a safety link 35 is pivoted at one end to the operating lever 20 adjacent the indicator pointer 29 and is provided with a slot 36 at its other end which slot engages an adjustable pivot member 37 with a sliding and rocking contact, which pivot member is rigidly engaged in the slot of the operating member. A tension spring 38 anchored preferably at one end to the operating lever pivot, or at that end to the safety link and at the other end to the member 37 on the operating member which spring is of less tension than that of the roller carrying link spring 17 and normally holds the innermost end of the slot of the safety link against the pivot member 37 of the operating member. This slotted pivoted safety link 35 and spring 38 act in the same manner as the pivoted safety arm blocks, safety arm and friction spring shown in the first four figures of the drawing. In the normal position the mercury switch tube is in the open position as shown in the dot and dash lines of Figure 5, with the operating mechanism parts as shown in Figure 6. As the Bourdon tube expands the safety link 35, held by spring 38 with the innermost end of slot 36 against the operating member pivot 37, rocks the operating member and related parts to the position shown in Figure 7 and upon further expansion of the Bourdon tube the spring 38 allows the slotted end of the safety link to travel over the fixed member 37 which is so adjusted on the operating member 14 that as the danger limit of the Bourdon tube is approached the outer end of the slot 36 engages the member 37 and throws the parts into the position illustrated in Figure 8, thereby breaking the circuit through the mercury switch tube 10. The springs 17 and 35 as the tube contracts return the moving parts to the normal position illustrated in Figure 2 without closing the circuit, as the inner end of the slot engages the member 37.

There is this difference between the forms shown in Figures 1 and 5. In the construction illustrated in the first four figures, the first movement outward of the operating lever 20, through the friction between spring arm 34 and safety arm rod 32, rocks the bracket plate 12 from the position shown in Figure 2 to that shown in Figure 3, further outward movement of the operating lever overcomes the friction but the spring 17 retains the rocking bracket plate 12 in the position shown in Figure 3 until the safety arm block 31 engages the enlarged end of the safety arm 32 and then further outward movement of the operating lever 20, having a direct engagement with safety arm block 19 through the rod 32, overcomes the tension of spring 17 and snaps the rocking plate 12 into the position shown in Figure 4. However, if at any point intermediate the position shown in Figure 3 and the engagement of the enlarged end of the safety arm rod the operating lever ceases in its outward movement and begins to move inward, then this inward movement is transmitted at once, through the friction between the spring arm 34 and safety rod 32, to cause the operating member to rock and immediately return the rocking bracket plate 12 to the position shown in Figure 2, thereby breaking the motor circuit. In the construction illustrated in Figures 5 to 8, inclusive, the safety link 35, with the slot 36 engaged by the member 37 carried on the operating member, through the spring 38 upon the first outward movement of the operating lever tilts the rocking bracket plate 12 from the position shown in Figure 6 to that shown in Figure 7, the spring 38 holding the inner end of the slot 36 against the member 37. Upon further outward movement of the operating lever, the tension of the spring 38 is overcome and the safety link slides over the member 37 until the outer end of the slot engages it and then on further movement in the same direction overcomes the tension of the spring 17 and rocks the operating member to snap the rocking bracket plate 12 to the position shown in Figure 8. However, should the operating lever cease its outward movement, after having rocked the parts to the position shown in Figure 7, at a point intermediate the length of the slot 36 and begin a movement in the opposite direction, the inward movement will not rock the operating member until the inner end of the slot 36 engages the member 37. Therefore the motor circuit is not broken until the inner end of the slot 36 rocks the operating member 14. It is to be noted that should the spring 17 fail by loss of tension or destruction, the weight of the mercury switch tube 10 carried on the extension 13 at one side of the pivot of the bracket 12 will immediately rock the bracket plate to the position shown in Figures 2 and 6, thereby immediately breaking the motor circuit. Should the spring arm 34 or the spring 38 fail to operate, the parts would remain in the position shown in Figures 2 and 6 or, should their failure occur after leaving the position shown in Figures 3 and 7, the parts would be returned to the first position by the safety rod or safety link when the danger limit is approached or, if the operating lever moves in the opposite direction, by end of the spring arm 34 engaging the safety block 19 or the outer end of slot 36 engaging the member 37. Should for any reason the Bourdon tube fail to contract to normal after having snapped the switch tube into open position through the safety rod or link, 130

as shown in Figures 4 and 8, then the parts would not return to normal and the mechanism would be inoperative to close the circuit until the cause had been removed.

5 As stated in the introduction, while a Bourdon tube and a snap movement switch mechanism are shown in the eight figures other types of prime mover instrumentalities with other types of switch mechanisms can be 10 employed to accomplish the same results.

For instance, a stack control, such as shown in Figures 9 and 10, is adaptable for the prime mover instrumentality, in which case the casing 1 would preferably be mounted 15 on or adjacent the stack 40 and is preferably carried on the sleeve 41, projecting from both sides the plate 42 secured to the stack, with a thermal or bimetal coil 43 surrounding the portion within the stack having one end secured to a post 44 carried on the stack plate and the other end fixed to a rotatable shaft 45 extending through the sleeves and passing through a cap 46 on the interior of the casing. The temperature in the stack upon 20 increasing will cause the thermal coil to expand thereby imparting a rotating movement to the shaft 45 in one direction and upon decreasing will cause the shaft 45 to rotate in the opposite direction which movement is 25 readily substituted for that of a Bourdon tube to impart the necessary movement to the operating lever 20, as hereinbefore described.

The stack control illustrated in Figure 9 also shows a switch mechanism in Figures 11 35 and 12 in which a resilient strip 48 is secured at one end to a block 47 of fibre, or other insulating material, adjustably secured by the set screw 49 upon the end of the shaft 45 projecting within the casing. A contact member 50 is mounted on the free end of the resilient strip adapted to be engaged with a corresponding contact member 51 mounted 40 upon a block 52 of fibre, or other insulating material, carried on the rear wall of the casing, with the binding posts 6 and 7 to which the leading in wires from the commercial or other current are connected having flexible connection 53 to the end of the strip secured to the block 47 and block 52, respectively. 45 In Figures 9 and 11 a fixed post or abutment 54 is provided extending outward from the rear wall of the casing in the path of the resilient strip 48 intermediate its ends. The block 47 is so adjusted upon the rotatable 55 shaft 45 and the abutment 54 is so located that when the stack is cool the contact members 50 and 51 will be separated or in the open circuit position, as shown in full lines in Figure 11. As the temperature in the 60 stack increases, as upon the ignition of the burner flame, the thermal coil will cause the shaft 45 to rotate, bringing the contacts 50 and 51 together and close the circuit and upon further increase in temperature to approaching the danger limit, or at a predetermined

temperature, the resilient strip 48 upon further movement of shaft 45 will engage this fixed abutment 54 and upon continued movement in that direction will cause the contact members to be moved apart and break 70 the circuit, as shown in dotted lines in Figure 11. As the temperature in the stack decreases the parts will resume the relations shown in full lines. Figure 12 illustrates a 75 wiping contact arrangement in which the abutment is omitted and the free end 55 of the strip is bent at an angle and carries the contact 50 with contact 51 carried on the under side of block 52. The normal position of the parts are shown in full lines. Upon rotation of the shaft 45 the contacts 80 will be brought into wiping contact and upon further movement the contact 52 will wipe across and beyond the face of contact 51 to the position shown in dotted lines and the 85 circuit broken. Upon cooling of the stack the parts will be returned to normal. The expansion and contraction movement of the free end of a Bourdon tube is also readily adaptable to rock the block carrying the 90 strip 48.

It is to be further understood that this safety switch mechanism may be most advantageously used in connection with a domestic oil burner system in which the oil and air are both furnished by an electric motor with this safety mechanism in the main motor circuit, however, it is just as applicable to any other type of fuel burner system employing an electrical control with this safety 95 mechanism in the control circuit. In the preferred type of fuel burner system it is customary to employ a room thermostat for actuating the burner mechanism as well as a boiler control, this improved safety switch being 100 105 an additional element to such controls.

What I claim is:

1. An electrical safety control switch including a moveable member for closing the circuit therethrough, an expandable and contractable prime mover for operating said movable member to close and break the circuit actuated by external conditions, and means operable after the circuit has been closed upon further actuation of the prime 110 115 mover in the same direction to break the circuit.

2. An electrical safety control switch including a moveable member for closing the circuit therethrough, an expandable and contractable prime mover for operating said movable member to close and open the circuit actuated by external conditions, and means operable after the circuit has been closed actuated by a predetermined condition of the prime 120 125 mover to break the circuit upon a continued movement of the prime mover in the same direction.

3. An electrical safety switch including a moveable member for closing the circuit 130

- therethrough, an expansible and contractable prime mover for said member actuated by external conditions normally maintaining the member in open position and upon a normal change of conditions moving said member 5 to close the circuit and maintaining it in closed position, and means actuated by an abnormal change of conditions causing further movement of the prime mover in the same direction to operate said member to 10 break the circuit.
4. An electrical safety switch mechanism including a moveable contact, an expansible and contractable prime mover therefor actuated automatically by external conditions to 15 close and break the circuit normally maintaining the contact in open position, adapted upon a predetermined change in conditions to close the circuit, maintaining the contact in closed position, upon a further predetermined 20 change in conditions actuating the prime mover in the same direction to break the circuit and maintain the contact in open position, and upon return to normal conditions to return the contact to the first position.
- 25 5. An electrical safety switch mechanism including a moveable contact and means operated automatically by an expansible and contractable prime mover actuated by external conditions to normally break the circuit and remain in open position, upon a predetermined change in conditions to close the circuit and remain in closed position under such conditions, upon further predetermined 30 change in conditions actuating the prime mover in the same direction to break the circuit and remain in open position, and upon the return of conditions to normal at any time to return the contact actuating means from the position occupied by it at the time 35 of the change to the first position.
- 40 6. An electrical safety switch mechanism including a movable contact member for making and breaking the circuit, an expansible and contractable member operatively connected thereto, means normally maintaining the contact in open position actuated by a predetermined expansion of said member to move the contact into closed position and in that position allow further predetermined expansion and thereafter to move the contact into open position and upon contraction toward normal from any amount of expansion to return the contact to the first 45 position upon initiation of contraction.
- 50 7. An electric switch safety operating mechanism including a mercury switch tube adapted to make and break the circuit therethrough carried in a rocking member normally in open position, a prime mover, and means between the prime mover and rocking member for normally holding the switch in open position and upon normal movement of the prime mover, to rock the switch tube 55 to closed position and hold it in such position
- during a predetermined amount of abnormal movement of the prime mover and upon continued abnormal movement therebeyond to throw the switch tube to open position and hold it in that position until the prime mover returns to normal. 70
8. An electric switch safety operating mechanism including a mercury tube switch adapted to make and break the circuit therethrough, a rocking member upon which the switch tube is mounted, an operating lever adapted to be actuated by a prime mover, and actuating means between the operating lever and rocking member normally maintaining the switch in open position and upon movement of the lever to first rock the switch to closed position, then allow further movement of the lever, and upon continued movement in the same direction to a predetermined point to throw the switch to open position. 75
9. An electric switch safety operating mechanism including a mercury tube switch adapted to make and break the circuit therethrough, a rocking member upon which the switch tube is mounted, an operating lever adapted to be actuated by a prime mover, and actuating means between the operating lever and rocking member normally maintaining the switch in open position and upon movement of the lever to first rock the switch to closed position, then allow further movement of the lever, upon continued movement to a predetermined point to throw the switch to open position, and, while, maintaining the switch in open position, allow the actuating means to return to normal upon movement of the operating lever to normal position. 80
10. An electric switch safety operating mechanism including a mercury tube switch adapted to make and break the circuit therethrough, a rocking member upon which the tube is mounted, an operating lever therefor, a Bourdon tube, an operative connection between the free end of the Bourdon tube and the operating lever, a pivoted operating member, a spring pressed roller carrying link pivoted at one end of the operating lever adapted to engage the roller with the rocking member, a slideable connection between the operating member and operating lever, means upon the sliding connection causing the operating member to be actuated by the operating lever to rock the switch tube to closed position upon normal expansion of the Bourdon tube, then allow a further independent movement of the operating lever in the same direction and upon further abnormal expansion of the Bourdon tube to actuate the operating member to return the rocking member to open position and an indicator pointer upon the free end of the operating lever adapted to travel over a scaled plate calibrated to indicate the degrees of the power causing the expansion of the Bourdon tube. 85 90
- 110 115 120 125
